United States Patent Office.

WILLIAM AURICH, OF CHICAGO, ILLINOIS.

Letters Patent No. 94,269, dated August 31, 1869.

IMPROVEMENT IN VAPOR-BURNERS.

The Schedule referred to in these Letters Patent and making part of the same.

To all whom it may concern:

Be it known that I, WILLIAM AURICH, of Chicago, in the county of Cook, and State of Illinois, have invented certain new and useful Improvements in Vapor-Burners; and I do hereby declare that the following is a full, clear, and exact description thereof, reference being had to the accompanying drawings, making part of this specification, and to the letters of reference marked thereon, like letters indicating like parts, wherever they occur.

To enable others skilled in the art to construct and use my invention, I will proceed to describe it.

My invention relates to vapor-burners; and consists in the construction and arrangement of a novel device for admitting atmospheric air into the same, so as to mix or unite with the gasoline, and also in the location and arrangement of the apertures through which the gas passes for burning.

In the drawings—

Figure 1 is a longitudinal section of my vapor-burner, and

Figure 2 is a side view.

In constructing my vapor-burner, I make a metallic tube, A, and rigidly attach to its upper end a cap, B, made so as to project all round, as clearly shown in figs. 1 and 2.

A short distance below the cap B, I make a series of apertures, *a*, in the tube A, as shown in the same figures, and, near the lower end of the tube, a couple of holes, *g*, immediately opposite each other.

Above the holes *g*, I pivot doors *f*, rigidly connected by a curved wire rod, *h*, and provided with a handle, D, so that they may be conveniently adjusted as desired, wholly or partially over the holes *g*.

The lower end of the tube I provide with a screw-thread, and insert therein a plug, C, having a corresponding screw-thread, for the purpose, as shown in

fig. 1, and also having a tapering or conical hole, *d*, the small end of which opens immediately under the holes *g*.

The plug C, I construct so that it may be conveniently attached to the pipe communicating with the petroleum or other reservoir.

In operating my vapor-burner, I connect it with the pipe leading to the reservoir, then heat it in any of the usual ways, when the gasoline will find its way through the conical hole *d*, into the tube A, immediately under the openings *g*, and mingling or uniting with the air admitted through these openings, will then pass out through the apertures *a*, when it may be lighted. The flame will heat the cap B, and with it the tube A, and in this way the supply of vapor will be kept up for the burner.

I am aware that there have been many devices used for supplying the gasoline with atmospheric air, as desired, and therefore I sought to make one of peculiar construction, that could readily and conveniently be operated, for the purpose desired. As the swinging doors *f*, composing it, are rigidly connected by the wire rod *h*, they are turned simultaneously, as the handle D is turned, and may be so adjusted as to admit as much or as little air as may be required.

Having thus described my invention,

What I claim, is—

As a new article of manufacture, a vapor-burner, consisting of the solidly-capped tube A, provided with holes *g* and apertures *a*, the swinging doors *f*, rigidly connected by the rod *h* and the plug C, all constructed and arranged for operating, as herein shown and described.

WM. AURICH.
